[57] **CLAIM**

The ornamental design for a headband for accommodating a night vision unit, as shown and described.

DESCRIPTION

FIG. 1 is a front perspective view of a headband for accommodating a night vision unit showing my new design; FIG. 2 is a front elevational view thereof;

FIG. 3 is a left side elevational view thereof, the right side is a mirror image;

FIG. 4 is a top plan view thereof;

FIG. 5 is a rear elevational view thereof; and,

FIG. 6 is a bottom plan view thereof.

The broken line showing of the bracket in FIG. 1 is for illustrative purposes only and forms no part of the claimed design.
